UNITED STATES PATENT OFFICE.

OLIVER W. RANDOLPH, OF TOLEDO, OHIO.

FURNACE.

Application filed March 27, 1925. Serial No. 18,736.

This invention relates to heaters.

This invention has utility when incorporated in warm air supply apparatus for delivering heated gases into a safety duct or 5 way.

Referring to the drawings:

Fig. 1 is a vertical section, with parts broken away, of an embodiment of the invention as a warm air supply, as for the operation of a drier in the removal of moisture 10 from material, as cereals;

Fig. 2 is a section on the line II—II, Fig. 1, looking in the direction of the arrow;

Fig. 3 is a section on the line III—III, 15 Fig. 2, looking in the direction of the arrow;

Fig. 4 is a perspective view of an air duct supply side delivery section as disposed under the fire door;

Fig. 5 is a perspective view of an open top 20 delivery duct section;

Fig. 6 is a perspective view of a fire pot side section;

Fig. 7 is a perspective view of a fire pot corner section;

25 Fig. 8 is a section of a duct on the line VIII—VIII, Fig. 3;

Fig. 9 is a side elevation, with parts broken away, showing the assembly of the furnace as a hot air supply source for a column type of 30 drier; and

Fig. 10 is a perspective view of the safety connection or louvre between the hot air supply and such drier to preclude reverse draft or combustion gas flow contrary to draft promotion control.

35 Furnace housing 1 as herein shown may be of masonry, and is provided with ash pit 2 having ash door 3. Bars 4 embedded in the masonry of the furnace housing 1 above the ash pit 2 carry grate ring 5 having horizontally extending grate bars 6.

This grate ring 5 has upwardly extending therefrom flaring grate prongs 7. Above this grate there is provided a fire pot 8 herein shown as comprising side sections 9 and corner sections 10 extending about the grate from fire door 11 through which the supply of hard fuel may be introduced into this fire pot 8 over the grate. These fire pot sections 9, 10, are provided with lugs 12 from which 40 extend brace bars 13 into the masonry housing 1 for maintaining these sections against spreading apart as the sections are slid into position over the heads of these brace bars 13 for having lower channel portions 14, 15, 45 rest upon duct edges 16, 17. The duct edge

16 rises adjacent openings 18 in duct 19 having its outer end 20 normally closed by damper 21 as gravity falling into closed position in said duct.

60 Adjacent the fire door 11 and therebelow is duct section 22 provided with damper 23 similar to the damper 21. This section 22 instead of having an upper outlet 18 has lateral openings 24 in communication with adjacent duct sections 19. Corner duct sections 25 have openings 26 similar to the openings 18 and adjacent the fire pot section supporting edge 17. There is, accordingly, provided herein a fire pot held rigid against outward shifting, but which fire pot may be readily removed for replacement as the sections deteriorate or warp in shape. Furthermore, the upward removal of the sections permit access 65 to the duct sides for cleaning as may be desired.

Above this fire pot 8 is combustion chamber 27 in communication with which is door 28 as a check draft. Above this combustion chamber 27 is a plurality of ducts 29 about 70 which the products of combustion may pass in ascent to pass by damper 30 into stack 31 as a normal take-off flue. As the fire is started in this heater or furnace, draft for combustion is supplied by way of ash pit 3 for passing up through the grate. As the fire gets under way the increase in draft is sufficient 75 to open the supplemental air duct dampers or valves 21, 23, and air from outside the furnace housing enters directly by way of passage 32 to rise around the fire pot 8, and thus be heated by the sections 9, 10. This air as 80 passing up around the fire pot 8 enters the combustion chamber 27 and may, with the damper 30 open, pass by way of the flue 85 stack 31.

The air as coming into the ducts 29 passes to air duct 33 as warm air not contaminated by any products of combustion. This duct 33, as herein disclosed, is connected to draft promotion means herein shown as fan 34 from which upwardly extends hot air supply 90 way 35 to column drier 36 down through which the material as grain, coal, rock or other granular substance to be acted upon, 95 may pass from supply end or hopper 37 to be delivered by way of discharge hopper 38.

With the heater under operation it may be desirable to supplement the warm air as delivered to the way 33, especially in those instances wherein the mingling of the products of combustion may not be detrimental to the 100 105 110

product being treated even though the product be of the type where the gases give up heat by direct contact instead of through a wall. For such supplemental supply of gases, damper 39 as mounted on hinges 40 may be swung by chain 41 into chamber section 42 of the combustion chamber 27 above the ducts 29. This damper 39 thus may take the hot gases as giving up some of their heat to the walls of the ducts 29 and throw such gases into the way 33 even with the damper 30 in the stack 31 opened. With the fan 34 in operation there is such induced draft in the way 33 that the damper 30 may be closed and sufficient draft provided for efficient operation of this furnace. For a still greater direct flow of the gases from the combustion chamber 27, ports 43 may be opened by slide valve 44 as operated by handle 45 and thus independently of the door 39 allow gases from the combustion chamber 27 to flow directly into the way 33 for drying timber or other material.

In the operation hereunder the fan 34 is shown as having belt 46 driving air compressor 47 for maintaining air supply in tank 48, the pressure of which may be indicated by gauge 49. Duct 50 from this tank 48 extends to thermostat 51 in hot air supply way 35 which is effective through lever 52 and chains 53, 54, for controlling the draft to the furnace below the grates or fire pot 8. This action is such that when the thermometer 55, as checking the thermostat 51, indicates that there is rise in temperature beyond that desired in practice, the draft may be checked automatically. Between the fan 34, as continuously driven during the operation hereunder, and this hot air supply way or duct 35 to the drying apparatus 36, is disposed a safety device precluding passing of high temperature fumes or products of combustion into the drier 36 when the fan 34 is not in operation. This safety device as herein shown comprises a louvre having vanes 56 normally closed by gravity. However, as the fan 34 is started sufficient pressure is maintained to open these louvres and thereby direct the supply of hot gases into the supply way 35. As the fan 34 is stopped the louvres 56 at once close.

No dust from the material in the drier 36 may come back into this fan 34 and have connection with the furnace for promoting spontaneous combustion. Accordingly, as to communication either way, and any danger inci-

dental thereto, this device is automatic in its safety construction.

What is claimed and it is desired to secure by Letters Patent is:—

1. A furnace comprising a grate, a primary flare fire pot adjacent the grate having openings extending upwardly thereabout, a secondary sectional fire pot rising from the primary fire pot, a furnace housing, and duct sections extending through the housing provided with sustaining connection means for said secondary fire pot sections. 60

2. A furnace comprising a grate, a sectional fire pot extending upwardly therefrom, a furnace housing, and duct sections extending through the housing having upwardly projecting seats astride which said fire pot sections are mounted. 70

3. A furnace comprising a grate, an annular series of fire pot sections extending upwardly therefrom, said sections downwardly terminating in grooved seats, a furnace housing, and horizontally extending box-shaped duct sections extending through the housing having upwardly projecting tongues for entering said fire pot section grooves. 75

4. A furnace comprising a grate, an annular series of fire pot sections extending upwardly therefrom, said sections downwardly terminating in grooved seats, a furnace housing, horizontally extending box-shaped duct sections extending through the housing having upwardly projecting tongues for entering said fire pot section grooves, said fire pot section having additional seats extending upwardly from said grooved seats, and headed means anchored in said housing for coacting with the additional seats as the grooved seats coact with the tongues, said fire pot sections being independently vertical shiftable 80 for placing and removal. 90

5. A furnace comprising a grate, a fire pot extending upwardly from said grate, a furnace housing, horizontally extending box-shaped duct sections extending through said housing, said sections providing mounting means for the fire pot with clearance as to the housing, said box-shaped ducts forming air passage from exterior of the furnace extending to pass upwardly about said fire pot, 100 and damper means in said box-shaped duct sections operable by draft in permitting air supply into the furnace about said fire pot. 105

In witness whereof I affix my signature.

OLIVER W. RANDOLPH.
